UNITED STATES PATENT OFFICE

91,075

DESIGN FOR A VEGETABLE BOWL OR SIMILAR ARTICLE

John Meredith Miller, Huntington, N. Y.

Application August 22, 1933. Serial No. 49,080

Term of patent 3½ years

To all whom it may concern:

Be it known that I, JOHN MEREDITH MILLER, a citizen of the United States, residing at Huntington, in the county of Suffolk and State of New York, have invented a new, original, and ornamental Design for a Vegetable Bowl or Similar Article, of which the following is a specification, reference being had to the accompanying drawing, forming part thereof.

I claim:

The ornamental design for a vegetable bowl or similar article as shown.

J. MEREDITH MILLER.
